UNITED STATES PATENT OFFICE.

CARL BROWN, OF DENVER, COLORADO, ASSIGNOR TO THE CHAMPION FORGING MACHINE COMPANY, OF DENVER, COLORADO, A CORPORATION OF COLORADO.

GAGING-DIES FOR ROCK-DRILLS.

1,053,474.

Specification of Letters Patent. Patented Feb. 18, 1913.

Application filed August 2, 1909. Serial No. 510,949.

To all whom it may concern:

Be it known that I, CARL BROWN, a citizen of the United States, residing in the city and county of Denver and the State of Colorado, have invented new and useful Improvements in Gaging-Dies for Rock-Drills, of which the following, together with the accompanying drawings, constitute a full, clear, and exact specification.

10 This invention relates to dies for gaging the cruciform drill bits used in rock drilling, to uniform sizes. The said dies are intended to be furnished principally with the machine for making and sharpening rock 15 drills and for general forging, upon which I have filed an application for U. S. Patent Serial No. 510,950 bearing even date here-with.

20 The object of the present invention is to provide a tool for gaging the thickness of the wings of rock drills and the amount of spread thereof, to such uniform dimensions as may be desired, and to accomplish this more quickly and efficiently than is 25 done at present.

A further object is to eliminate skilled hand labor in this step of drill making.

While the primary purpose is to use this 30 invention in connection with the machine referred to, yet these dies may be mounted in an individual framework and used separately in cases where this may seem desirable.

The present drawings show these dies as 35 forming a part of the machine above mentioned but any skilled designer of machinery can readily see how to construct a simple individual framework containing the necessary elements for a separate machine.

40 In the accompanying drawings, Figure 1 is a front elevation of the dies in working position. Fig. 2 is a section taken on the lines 2—2, (Fig. 1) and Fig. 3 is an elevation taken from the lines 3—3, (Fig. 2) 45 and in the direction indicated by the arrows.

The steel of which the drill is being made comes to these dies after having been operated upon by the opening dies, as explained in the application for U. S. patent 50 already named.

Referring to the drawings, (3^a) and (3^b), are parts of the tool wheel disks of my machine, the sleeves (3^c) and (3^d) extend-

ing outward respectively from (3^a) and (3^b). The block (15^b) forms the relatively 55 stationary part of the dies and (15^a), is the relatively movable part. (15^b) is secured in the sleeve (3^d) by pins (3^e). In constructing an individual machine, the parts (3^a) and (3^b) would form a portion of the 60 framework of the machine and these two parts would, of course, be rigidly connected to each other so as to allow the proper working of the dies. The movable part (15^a) of the dies is held normally in the 65 retracted position by the spring (6), which is in compression between the pins (3^f) and (15^f). A tapering stop (20), which is adjustable back and forth and having an L-shaped cross section, is slidably disposed 70 in a corresponding groove formed in the front face of block (15^b). A straight bar (21), having a foot (21^a), the latter carrying the upright stop (21^b), is connected to (20) at the latter's lowermost extremity 75 by the bolt end (20^x) passing through an elongated eye (21^c) in the extremity of (21^a). Bar (21) slides over the face of (3^b) in the guides (23) and may be adjustably held in a number of different positions by 80 the pin (24^a) attached to the spring handle (24) and engaging various corresponding holes (25), arranged on the face of (3^b). (15^a) and (15^b) have the tapering recesses (15^x), (15^y), respectively, cut in their 85 opposing faces. The taper of these recesses corresponds to the taper desired on the sides on the drill wings. The drill wings are flattened out between the opposing faces of (15^a) and (15^b) and the thickness of the 90 drill wings is determined by position of the adjustable stop (20) which limits the distance of approach between (15^a) and (15^b), the latter at the same time gaging the amount of spread of the wings. By moving the bar (21) back and forth, the depth stop (21^b) is moved back and forth to the corresponding degree in the recess (15^y), and the lateral stop (20) is moved in or 95 out in the same proportion. It will be noticed that the same ratio will constantly 100 exist between the depth to which the drill is admitted into the dies and the distance to which the stop (20) projects from the face of (15^b). (28), (28), are arms extending from the 105

shaft (26), and having their slotted ends in engagement with the two extremities of pin (15^a); operating lever (27), is rigidly attached to the shaft (26) at any convenient point. The position of (27) at the other extremity of its stroke is shown in dotted lines. The purpose of the device just explained is to retract (15^a) in case the spring pressure should, at any time, be insufficient to accomplish this.

In using the dies, the adjustable stops are first brought to the desired positions by means of the spring handle (24) and pin (24^a) engaging one of the corresponding holes (25). The drill steel is inserted into the dies from the front and the depth to which it is admitted is determined by the stop (21^b). The hammer (5) is then allowed to strike (15^a), forcing it forward against the drill steel until it is stopped by (20), thus flattening out two of the wings of the drill to the required gage, and at the same time, drawing down the amount of spread of the opposite wings to the corresponding gage. The drill steel is then withdrawn from the dies and turned through an angle of 90 degrees and again inserted into the dies as before, when the hammer is allowed to strike (15^a) as before, thus gaging the thickness of the second pair of wings and gaging the amount of spread of the first pair. An anvil block (9), back of the stationary die, is provided for taking up the shock produced by the striking of the hammer (5).

Having fully described my invention, what I claim as new, is:—

1. In gaging dies for rock drills, consisting of two principal parts, a relatively stationary one and a relatively movable one, and having directly opposed working faces, the combination therewith of a slidable wedge, suitably disposed in one of the said principal parts, the said slidable wedge being adapted to be drawn back and forth, and thereby to variably limit the distance of approach toward each other of the two said principal members, substantially as, and for the purpose, described.

2. In gaging dies for rock drills, the combination with two principal forming members, of a suitably disposed slidable wedge in engagement with one of the said principal members; a spring handle slidably arranged on the same principal member; a slotted foot projecting from the said spring handle and engaging one extremity of the said slidable wedge; a depth gage mounted on the said projecting foot, and means for rigidly holding the said spring handle in any one of several predetermined different positions, as, and for the purpose specified.

In testimony whereof, I have signed my name to this specification in the presence of two subscribing witnesses.

CARL BROWN.
